Patented Nov. 10, 1914

UNITED STATES PATENT OFFICE.

HARRY W. LEE, OF BALTIMORE, MARYLAND, AND ARTHUR G. PIERCE, OF TOLEDO, OHIO.

BILLIARD-CUE TIP.

1,116,827.

Specification of Letters Patent.

Patented Nov. 10, 1914.

Application filed March 12, 1914. Serial No. 824,221.

To all whom it may concern:

Be it known that we, HARRY W. LEE, a citizen of the United States, residing in the city of Baltimore, and State of Maryland, 5 and ARTHUR G. PIERCE, a citizen of the United States, residing at Toledo, in the county of Lucas and State of Ohio, have invented certain new and useful Improvements in Billiard-Cue Tips; and we do declare the following to be a full, clear, and exact description of the invention, such as will enable others skilled in the art to which it appertains, to make and use the same.

This invention relates to new and useful 15 improvements in billiard cues and the primary object of the invention is to provide an improved means for retaining the tip on the cue stick.

A further object of the invention resides 20 in providing an end for cues which is adapted to supersede the present ivory ferrule now in use on cues, which end possesses all of the advantages of the ivory ferrule and obviates the disadvantages thereof.

25 A further object of the invention resides in providing a celluloid ferrule applied on a tenon and to the outer end of which is applied a fiber ring or collar.

Still another object of the invention resides 30 in providing a construction which is simple and durable in construction, inexpensive to manufacture, and one which will be very efficient in use.

With these and other objects in view, our 35 invention consists in the novel features of construction, combination and arrangement of parts, as will be hereinafter referred to and more particularly pointed out in the specification and claims.

40 In the accompanying drawings, forming a part of this application: Figure 1 is a fragmentary elevation of a billiard cue constructed in accordance with our invention; Fig. 2 is a longitudinal section therethrough; Fig. 3 is a plan view of the end of the cue with the tip removed; Fig. 4 is a horizontal section through the device, as seen on line 4-4 of Fig. 1; Fig. 5 is a detail perspective view of the cue end with the 45 parts separated one from the other; and Fig. 6 is a longitudinal section through a slightly modified form of cue end.

It is a well-known fact among manufacturers of billiard cues and expert handlers 50 thereof, that it is desirable to have a white

end on the cue in view of the fact that it is neat appearing, affords firmness at such point, and most important, aids in sighting the ball. In the manufacture of the finer billiard cues now in use, an ivory ferrule is 60 provided at the end of the cue, the same being carried on a reduced portion or tenon on the cue. It is also a fact that ivory is quite brittle, so that in order to be effective to withstand considerable wear, such an ivory ferrule must be of considerable thickness. In manufacturing an ivory ferrule of such thickness, however, it is necessary, of course, to reduce the diameter of the tenon and by such reduction, the cue is materially 70 weakened at a point receiving the greatest strain. Aside from the fact that ivory is expensive, it will be seen, therefore, that there is a great disadvantage in using an ivory ferrule, and we contemplate overcoming this disadvantage by the use of a celluloid ferrule.

In describing the invention, we shall refer to the drawing in which similar reference characters designate corresponding parts throughout the several views, and in which—

1 indicates a cue stick of the usual or any preferred type which is reduced at the outer end thereof to provide a tenon 2 of a diameter greater than the diameter of tenons which have heretofore been provided on cue sticks. The provision of this tenon obviously produces a shoulder 3 between the tenon and the cue stick proper and the extreme outer end of this tenon is again reduced to provide a smaller tenon 4. The shoulder between the smaller tenon 4 and the tenon 2 is indicated in the drawing as 5.

Applied to the tenon 2 to fit snugly thereon and rest against the shoulder 3 is a ferrule 6 formed of celluloid, the same being of such thickness as to fit flush with the outer periphery of the cue stick 1 and the outer peripheral edge of this ferrule fits flush 100 with the face of the shoulder 5.

As indicated above, we desire to provide a celluloid ferrule in place of an ivory ferrule, in view of the fact that it is cheaper to manufacture and will enable the main tenon to which the same is applied to be of considerably larger diameter than may be provided with the use of an ivory ferrule. It is a fact, however, that cement and the like will not adhere to celluloid, so that the cue 110

tip proper may not be applied directly to the outer peripheral edge of this sort of ferrule. We, therefore, employ a ring or collar 7 which is preferably formed of fiber 5 and applied to the outer and smaller tenon 4 to rest against the shoulder 5 and the outer peripheral edge of the ferrule 6. This collar fits snugly on the tenon 4, the outer diameter of the same being such as to fit 10 flush with the outer periphery of the ferrule and the outer peripheral edge of said collar or ring fits flush with the outer end of the tenon 4. In order to secure this ring or collar 7 in place, the same is cemented to the 15 shoulder 5 and the tenon 4, as indicated at 8, and the inner peripheral edge of said collar at its bottom face is chamfered as indicated at 9, thus permitting a greater surface with which the cement may adhere. 20 It will be understood that after the application of the collar or ring 7 in place, a flat surface will be provided, the outer face of said ring or collar fitting flush with the outer end of the tenon 4, and it will also be 25 understood that cement or the like will readily adhere to both materials, *i. e.*—the wood and the fiber. A leather cue tip 10 is then cemented or otherwise similarly secured to the outer face of the ring or collar 30 7 and the outer end of the tenon 4, and when so applied, the same will be secure in its fastenings.

In Fig. 6, we have shown a slightly modified form of the invention in which a cue stick 11 is provided, the outer end thereof being reduced to form a single enlarged tenon 12. This tenon is preferably of the 35 same diameter as the tenon 2 referred to in the other form, and a celluloid ferrule 13 is employed to fit snugly over the tenon and rest against the shoulder formed between said tenon and stick proper. This ferrule is not, however, of a length equal to the length 40 of the ferrule in the other form, but is slightly shorter than this tenon. A fiber ring or collar 14 is also employed, the same being somewhat similar to the ring or collar 7, but having a larger inner diameter to fit snugly on the tenon 12 at the outer end 45 with the ferrule 13. When this ring or collar 14 is applied, the same rests against the outer peripheral edge of said ferrule and the same is cemented on its inner edge only to said tenon. The outer peripheral edge of 50 this collar or ring 14 fits flush with the outer end of the tenon 12 when said ring or collar is properly applied, and a tip 15 is cemented or otherwise similarly secured to the outer edge of the collar or ring 14 and the outer 55 end of the tenon 12, as in the first mentioned form. It will be seen, therefore, that in this form of the device, the construction is quite similar to that of the first mentioned form, the difference being the omission of the 60 outer or other reduced tenon and the en-

gagement of the fiber collar or ring on its inner periphery with the tenon which it encircles.

From the foregoing description of the construction of our improved cue tip, it will be seen that a construction is employed which possesses all the advantages of a cue construction wherein an ivory ferrule is provided and which, at the same time, obviates the disadvantages incurred by the use 70 of the last mentioned ferrule. It may still further be seen that in the construction employed, a cue is provided which is more simple in construction, less expensive to manufacture, and equally as efficient in use, 75 as any heretofore known.

While we have particularly described the elements best adapted to perform the functions set forth, it is obvious that various changes in form, proportion, and in the 80 minor details of construction may be resorted to without departing from the spirit or sacrificing any of the principles of the invention.

Having thus described our invention, 90 what we claim is:

1. A billiard cue comprising a cue stick reduced at its outer end to provide a tenon thereon, a celluloid ferrule applied on said tenon to fit snugly thereon, a collar applied on the tenon and secured thereto to rest in contact with the outer peripheral edge of said ferrule, and a tip secured to the outer edge of said collar and the outer end of said tenon.

2. A billiard cue comprising a cue stick reduced at its outer end to provide a tenon thereon, the outer end of said tenon being in turn reduced to provide a second and smaller tenon at the extreme outer end of said stick, a ferrule applied to the first mentioned tenon to fit snugly thereon, the periphery of said ferrule fitting flush with the periphery of the cue stick and the outer peripheral edge of said ferrule fitting flush with the shoulder formed between said tenons, a collar applied on the additional tenon and secured thereto, the outer periphery of said collar fitting flush with the periphery of said ferrule and the outer peripheral edge of said collar fitting flush with the outer end of the additional tenon, and a tip secured to the surface formed by the outer peripheral edge of said collar and the outer end of said additional tenon.

3. A billiard cue comprising a cue stick reduced at its outer end to provide a tenon thereon, the outer end of said tenon being also reduced to form an additional and smaller tenon at the extreme outer end of said stick, a celluloid ferrule applied on the first mentioned tenon to fit snugly thereon, the outer peripheral edge of said ferrule fitting flush with the face of the shoulder formed between said tenons, a fibrous collar 130

applied on the additional tenon and secured thereto and to the face of the shoulder between said tenons, the inner periphery of said collar being chamfered adjacent the inner face thereof, the outer peripheral edge of said collar fitting flush with the outer end of said additional tenon to provide a flat surface, and a cue tip secured to the last mentioned surface.

In testimony whereof we have hereunto set our hands in presence of two subscribing witnesses.

HARRY W. LEE.
ARTHUR G. PIERCE.
